United States Patent Office

Des. 177,190

Patented Mar. 20, 1956

177,190

TRUCK CAB

Theodore Ornas, Jr., Fort Wayne, Ind., assignor to International Harvester Company, a corporation of New Jersey

Application December 22, 1954, Serial No. 33,654

Term of patent 7 years

(Cl. D14—3)

FIG. 1

Des. 177,190

PAGE 2

The dot-dash line shown in the drawing figures is for illustrative purposes only.

I claim:

The ornamental design for a truck cab, substantially as shown and described.
